(57) **CLAIM**

The ornamental design for a hand-held sensor, as shown.

DESCRIPTION

FIG. 1 is an isometric view of the hand-held sensor;

FIG. 2 is a top view thereof;

FIG. 3 is a bottom view thereof;

FIG. 4 is a front view thereof;

FIG. 5 is a back front view thereof;

FIG. 6 is a right side view thereof; and,

FIG. 7 is a left side view thereof.
